Adjustable supports for shelving and similar structures and methods of applying same thereto, and combinations therewith, and in particular, to a support for shelving having a plurality of apertures vertically arranged in two rows, and a method of applying such support to a cabinet or bookcase.

Adjustable supports for shelving and similar structures and methods of applying same thereto, and combinations therewith, and in particular, to a support for shelving having a plurality of apertures vertically arranged in two rows, and a method of applying such support to a cabinet or bookcase.

UNITED STATES PATENT OFFICE

2,354,269

ADJUSTABLE SUPPORT FOR SHELVING

Adolph Marchand, Jackson Heights, N. Y.

Application December 28, 1943, Serial No. 515,914

3 Claims. (Cl. 248—241)

Present invention relates to adjustable supports for shelving such as used in cabinets and bookcases and many other structures employing shelves. A specific object of this invention is to provide a combination which consists of opposed channel plates for securing to the vertical sides of a cabinet, for example, each channel plate being provided with two vertically arranged rows of apertures. Said apertures receive latching lug members carried by shelf-holding brackets, each bracket including a pivoted member which, when swung down in line with its carrying member, will securely latch the bracket to the channel plate, and at the same time enable ready removal of the bracket and its replacement to a new position whenever required.

The invention will be described with reference to the accompanying drawing, in which

Figure 1 is a perspective view of a cabinet containing an embodiment of the invention, the figure being partly broken away.

Figure 2 is a fragmentary isometric view showing cross-section of one of the two channel plates, and one of the brackets in position thereon.

Figure 3 is a front elevation showing in full line the position of one of the brackets on a section of the channel plate appurtenant thereto and showing in dotted lines the position of the pivoted latching member of the bracket when the bracket is applied to the plate and prior to movement into locking position.

Figure 4 is a horizontal section on the line 4—4, Figure 3.

Figure 5 is an enlarged longitudinal section through one of the brackets and the holding plate.

Figure 6 is an enlarged vertical section on the line 6—6, Figure 5.

Referring to the drawing, I have shown at 1 a conventional form of cabinet having a door 2. Each of the vertical walls of the cabinet will have secured thereto, as by spot-welding or other securing media a channel plate 3. In many cases, however, as where the side walls of the cabinet or bookcase are of metal, the channel plate may be omitted, because function of the channel plate is to provide two rows of apertures, vertically positioned in the usual case, and having a space behind the wall in which the apertures are formed. Frequently, in metal cabinet construction, the side walls may have these rows of apertures punched in them, and the customary mounting of the cab-

inet in or exterior to a receiving recess will enable the provision of a reasonable spacing between the side wall and an opposite surface.

The shelf-holding brackets forming the embodiment illustrated in the drawing, are designed to receive the shelving and in such manner that a shelf is held at both top and bottom and may be inserted into the appropriate brackets by a sliding movement.

10 The brackets are indicated at 4, 4x. The member 4 of the bracket consists of a plate stamped into U shape so that it has upper and lower flanges spaced to receive a shelf. Preferably, the bracket section 4 is cut and punched inwardly to provide a hook 5, and it is formed with an aperture to receive the headed latch bolt 6 which turns freely relative to said bracket member 4.

15 The bracket member 4x is of similar form as to the top and bottom flanges and it receives and is secured to the said latch bolt 6 so that when bracket member 4x is pivotally moved, the latch bolt will have corresponding movement, i. e., rotation. The latch bolt may be welded to bracket member 4. A second and convenient method is to form part of the shank of the bolt square or out-of-round, and to press such section of the bolt into a corresponding aperture in member 4x, whereupon the bolt can be headed upon bracket member 4, this arrangement being illustrated in Figure 6.

20 As shown in Figures 2 and 3, and also in Figure 4, part of the top flange of bracket member 4x will be cut away adjacent to the corresponding flange of bracket member 4, to permit member 4x to be swung to the dotted line position Figure 3.

25 Bracket member 4x in the dotted line position of Figure 3 will hold the elongated latch head 6x of latch bolt 6 in such position that it may be placed in or withdrawn from the appropriate aperture of the channel plate 3. When, however, bracket member 4x is swung to full line position, as shown in Figures 3 and 6, for example, the elongated latch head will have its ends extended above and below such aperture and the bracket will be securely latched to the channel plate.

30 In applying the bracket to the channel plate, member 4x is moved to the dotted line position 3, and thereupon the latch hook 5 is inserted into a selected one of the front row apertures of the channel plate (or a corresponding aperture formed directly in a cabinet side wall), the latch head having been placed in the appropriate aper-

ture of the second row, member $4x$ is swung down to be in line with member **4** and the action is completed. Each set of two brackets will then be ready to receive a shelf **4**, the latter being inserted by a sliding movement. By appropriately spacing the flanges of the brackets in accordance with the thickness of the shelving, or vice versa, the shelving is frictionally held and requires no additional holding media.

It will be understood that various changes may be made in the form of the bracket, without departing from the spirit of the invention. For example, the bracket members can be so made as to provide only one holding flange for the shelving, if desired. Also, when a single flange arrangement is employed, the flanges of two bracket members, or one of them may be apertured to receive screws or studs for entering apertures formed in shelving and the shelving may thus be fastened to the brackets. In such case, the bracket member to which the elongated latch head is fastened may have a movement away from the shelving to release the bracket from the channel plate or cabinet side walls.

Having described my invention, what I claim and desire to secure by Letters Patent is as follows:

1. An adjustable support for shelving comprising a bracket having two mutually pivoted members, one member carrying a projected latch hook and the second member carrying the pivot

device by which the two members are mutually pivoted, in such manner that movement of the second member imparts rotation to the pivot device, the pivot device having an elongated latch head.

2. An adjustable support for shelving comprising a bracket consisting of two members, each formed with spaced flanges adapted to receive a shelf between them, a pivot member connecting the two bracket members and secured for rotation with one of said bracket members, an elongated latch head being carried by said pivot member, and a latch projection carried by the bracket member companion to the bracket member which carries the pivot member.

3. An adjustable support for shelving comprising a bracket consisting of two members, each formed with spaced flanges adapted to receive a shelf between them, a pivot member connecting the two bracket members and secured for rotation with one of said bracket members, an elongated latch head being carried by said pivot member, and a latch projection carried by the bracket member companion to the bracket member which carries the pivot member, and a pair of channel plates for co-acting with a plurality of said bracket members, each channel plate having a plurality of rows of apertures adapted to receive the projections and latch heads of said brackets.

ADOLPH MARCHAND.
